UNITED STATES PATENT OFFICE.

HENRI VICTOR BEAUFILS, OF PÉRIGUEUX, FRANCE.

MECHANICAL BILLIARD-CUE.

SPECIFICATION forming part of Letters Patent No. 673,753, dated May 7, 1901.

Application filed February 14, 1900. Serial No. 5,164. (No model.)

To all whom it may concern:

Be it known that I, HENRI VICTOR BEAUFILS, of Périgueux, France, have invented a new and useful Improvement in Mechanical Billiard-Cues, of which the following is a specification.

This invention relates to an improved mechanical billiard-cue, which is more particularly adapted for use with small billiard-tables and is designed to permit the players to remain seated and to avoid the necessity of displacing the billiard-table.

The invention consists in providing each end of the mechanical cue with a tip, one of these tips being operated directly by a spring which actuates the cue and the other by the reaction resulting from the expansion of the said spring. To employ a very simple comparison, one of the tips may be taken to produce an effect of the same kind as that of a projectile thrown by a firearm and the other tip to produce an effect similar to that resulting from the recoil of the arm.

This improved cue permits of adjusting to any desired degree the force of the stroke intended to be given to the balls by providing means whereby the one tip is utilized for energetic strokes and the other for less energetic strokes, the variations in the intensity for intermediate effects being obtained by holding the tip at a greater or less distance from the ball at the moment of liberating the spring.

In order that my invention may be clearly and readily understood, I will now describe the same with reference to the accompanying drawings, in which—

Figure 1 shows a longitudinal section of the improved cue in its normal position of rest. Fig. 2 is a similar view, but cocked ready for striking. Fig. 3 is also a similar section indicating the extreme position the cue takes immediately after its liberation, and Fig. 4 is a transverse section taken on the line A B of Fig. 2.

In carrying the invention into practice the improved cue is formed of a tubular cylindrical body or casing *a* of any convenient section, which is closed at one extremity by means of a stopper or plug *b* and at its other end by a perforated cap *c*, designed to be

freely traversed by a rod *d*, carrying one of the tips *e*. A ferrule or rod *o*, integral with the plug *b*, and consequently with the tube *a*, is fitted with the other tip *p*. The plug *b* and the cap *c* may be secured to the extremities 55 of the tube or casing by screwing or in any other convenient manner. The rod *d* is formed with a collar or cylindrical shoulder *f* of such a diameter as to enable it to slide freely within the tube or casing *a*. On each side of this 60 collar is provided two helical springs *r s*, the stronger one, *r*, being arranged between the shoulder *f* and the plug *b*, while the other spring *s*, which is much weaker, is located between the said shoulder *f* and the cap *c* at 65 the opposite end of the tube. In the said collar *f* is formed a groove *g*, which corresponds to and fits a longitudinal rib *h*, provided in the interior of the tube *a*, the object being to guide the rod and to prevent it 70 from turning during its longitudinal movement. A hole or cavity formed in the shoulder *f* serves to receive a pin or stud *i*, provided with a small helical spring *k*, disposed at the bottom of the hole and tending to press 75 the pin or stud *i* outwardly from its cavity. At the point in the tube *a* corresponding to the innermost limit of the stroke of the collar *g* there is formed an aperture *l*, which affords passage to the said spring pin or stud, 80 and facing this aperture *l* is a button *m*, attached to the end of a blade-spring *n*, fixed in the interior of the tube *a*.

The operation of my improved cue is as follows: The cue being in its normal condition, 85 as shown in Fig. 1, is held by its tubular part, and the tip *e* is then pressed against any convenient stationary object. This causes the rod *d* to enter the interior of the tube *a* by compressing the spring *r* until the pin or stud 90 *i* is opposite the aperture *l* in the casing *a*. The spring *k* at the back of the stud *i* then presses the same forward into said aperture *l* and causes it to engage against the inner portion of the button *m*. In this manner the 95 cue is cocked ready for use, as shown in Fig. 2.

For causing the cue to strike it is only necessary to press with the finger upon the spring-button *m*, which latter then presses the stud *i* inward until the rod *d* is released, where- 100

upon the spring *r* expands and projects the rod *d*, fitted with its tip *e*, forward, while at the same time producing by reaction the recoil of the tube *a* and tip *p*, secured thereto 5 at the opposite end, as shown at Fig. 3.

The front or weaker spring *s* has for its object to gradually reduce the force of the stroke.

According to whether it is desired to obtain 10 a more or less energetic blow upon the ball, and thus to either increase or reduce the intensity of the effect, the blow should be effected either by the main tip—that is to say, by direct stroke—or by the tip *p* at the opposite 15 end, and so act by the force of the recoil. It will be understood that the amount of movement of the tip *p* due to reaction or recoil will depend upon the manner in which the 20 cue is held, a light pressure in holding the cue permitting a greater movement of the tip *p* than a firmer hold on the cue. By placing the tip at a greater or less distance from the ball at the moment of striking it will be 25 easy, owing to the action of the counter-spring *s*, to alter the intensity of the effect.

I wish it understood that I do not limit myself to the exact form, dimensions, or details of construction herein described by way of an example, as the device may obviously be 30 modified without departing from the nature 35 of the invention.

What I claim is—

1. An improved mechanical cue furnished with a tip at both ends, one of which is operated in a direct manner by the expansion of 35 a spring or other motive power which may be used for operating the cue, while the other tip

operates by the reaction resulting from the stroke substantially as described.

2. In a mechanical cue the combination of 40 a tube fitted at its rear with a tip, a rod arranged partially in such tube and provided at its outer extremity with a second tip, the said rod being connected with the tube by an intermediary operating-spring, a second or 45 counter spring, and a catch, so arranged as to cause the operating-spring to simultaneously affect both tips, one in a direct manner by the expansion of the spring, and the other by the recoil of the tube produced by the 50 reaction, while permitting the intensity of the stroke to be varied by using the one or the other of the two tips at a greater or less distance from the ball substantially as described.

3. In a mechanical cue the arrangement of 55 a plug-ferrule furnished with a tip, and secured to the rear of a mechanical cue, in which the action is obtained by the projection of a rod provided with a tip, under the sudden expansion of an operating-spring, for the object of utilizing the recoil of the cue under 60 said expansion of the operating-spring such cue being specially intended for use with small billiards or the like so as to permit the player to remain seated without displacing 65 the billiard-table substantially as described.

In testimony whereof I have signed my name to this specification in the presence of two subscribing witnesses.

HENRI VICTOR BEAUFILS.
